F. BRUA.
HARVESTER RAKE.

No. 60,993.

Patented Jan. 8, 1867.

Inventor: Franklin Brua.

United States Patent Office.

FRANKLIN BRUA, OF GORDONVILLE, PENNSYLVANIA.

Letters Patent No. 60,993, dated January 8, 1867

IMPROVEMENT IN HARVESTER RAKES.

The Schedule referred to in these Letters Patent and making part of the same.

TO ALL WHOM IT MAY CONCERN:

Be it known that I, FRANKLIN BRUA, of Gordonville, in the county of Lancaster, and State of Pennsylvania, have invented a new and useful improvement in the combination and arrangement of Raking Attachment to Reaping Machines; and I do hereby declare that the following is a full, clear, and exact description of the construction and operation of the same, reference being had to the accompanying drawings, and to the letters of reference marked thereon, making a part of this specification, in which—

Figure 1 is a perspective view of the platform Q, supporting column A, with the horizontal rake-bearing wheel and parts in place.

Figure 2 is a top and a side view of the cogged wheel O, with its centrally raised and slotted arms.

Figures 3, view of each separate part in detail and detached.

The nature of my invention consists in the arrangement and construction of a horizontal wheel, cogged beneath and provided with stops or lugs on its upper surface, and slotted radiating arms carrying the rakes with it in its revolutions, and causing the several rakes to rise and fall by the intervention of a cam, affixed to the vertical shaft, around which the rake-wheel revolves as its centre.

To enable others skilled in the art to make and use my invention, I will proceed to describe its construction and operation.

On an upright post, A, is the double head, B, or socket bracket, for the reception of a vertical shaft, I, figs. 3. To this shaft, I, the slightly-dished cam G, with its outer bevel edge, is firmly affixed; next below the cam G there is a curved guard-plate, C, with an ear perforated for the passage of said shaft I. There is also a bracket, D, with an annular end, for embracing said shaft I, beneath the curved guard C; this elbowed bracket, D, supports a bevel pinion, F; these several parts are secured by a stout nut, E, affixed to the screw end, e, of the vertical shaft, I. The cogged rake-wheel O, fig. 2, is slipped down over the shaft I, from above, having its bearing in the centre of the four centrally-elevated and slotted radiating arms M; the rakes and gatherer, T, are provided (on their shafts) with a socket, K, and curved heel, L, terminated by an end provided with a friction-pulley, l, or otherwise; this curved heel L enters the slot m of the radiating arms M, and is held by a pivot between said slots m, while the shafts of the rakes are each held by their connection with the socket trough K and heel L. Two of the shafts, T, are shown provided with rakes, alternating with the other two, bearing simply reel-like gatherers or arms, fig. 1. The platform and reaping machine being no part of my invention, may be of any of the kinds in use, adapted to the application of said raking attachment. The operation will be readily understood. To give a revolving motion to the pinion F from the machine, when in motion, by means of a chain or other gearing, will carry the shafts T of the rakes, connected by a pivot in the slots of the radiating arms, M, of the horizontal cogged-wheel O, into which the pinion F meshes. The curved heel L, coming in contact with the edge of the cam G, presses the lower end out gradually, which causes the shaft to rise upwards at the point, after having swept over the platform, and the rake or blind thus raised continues in this elevated position, so as to clear the driver, seated on the machine, and as the edge of the cam G is so graduated as to bring the rake gradually down with its teeth in close proximity to the platform, in a line with the cutting-bar, in which position it is held by the terminus, l, of the shaft, coming between the curved guard-plate C and back portion of the cam, so that the rake cannot be pressed upwards from the platform until after said heel or terminus, l, has cleared the guard, at the point its office is performed, to keep the heel of the shaft firm, so as not to yield to pressure laterally, or backwards, while raking off heavy grain. The upper side of the wheel O is provided with a stud, P, to each radiating arm, M, against which stud or lug, P, the heel L of the shaft is made to bear; thus while the rakes fall and rise within the slotted arms with ease, the guard-plate and lugs support them in performing their office as they successively follow each other over the platform, acting with great precision. The screw-nuts H and E will hold and confine the several parts on the shaft.

What I claim as my invention, and desire to secure by Letters Patent, is—

The peculiar construction of the horizontal wheel O, with its stops or lugs P, centrally-elevated radiating arms M, with their slots m, in combination with the elbowed heel K L, of the rake-shaft T, the whole being arranged and operated in the manner and for the purpose herein set forth.

I also claim the arrangement of the double head B, centre-pin or shaft I, bracket D, pinion F, and slotted cog-wheel O, when constructed and operated in the manner and for the purpose set forth.

FRANKLIN BRUA.
